Primary Examiner — Calvin E Vansant*Assistant Examiner* — Pia J Marchetti(74) *Attorney, Agent, or Firm* — Lippes Mathias LLP(57) **CLAIM**

The ornamental design for a roof rack rod attachment as shown and described.

DESCRIPTION

FIG. 1 is a perspective view from above of the roof rack rod attachment showing my new design;

FIG. 2 is a front plan view thereof;

FIG. 3 is a rear plan view thereof;

FIG. 4 is a side elevation view thereof;

FIG. 5 is the other side elevation view thereof;

FIG. 6 is a top plan view thereof;

FIG. 7 is a bottom plan view thereof; and,

FIG. 8 is an environmental perspective view thereof.

The details shown in broken or discontinuous lines in the accompanying drawings are to be disregarded when considering the overall impression of the design.

1 Claim, 8 Drawing Sheets(56)
